UNITED STATES PATENT OFFICE.

NERI J. PETITCLERC, OF ST. LOUIS, MISSOURI.

FUEL ECONOMIZER.

Application filed December 24, 1925. Serial No. 77,659.

This invention relates broadly to fuel economizers adapted to promote efficient combustion of fuel; and has more particular reference to means for preheating the air supplied to the fire-box or combustion chamber of a furnace, boiler, and the like.

An object of the present invention is to provide a device of the character described which is so formed that it may be readily and conveniently installed in any form of fire box that is provided with the usual fire door.

Another object is to provide a preheater which may be readily removed from the fire box and taken apart for the purposes of inspection, cleaning, repairs, and the like.

A further object is to provide a preheater which is withdrawn automatically from the fire box whenever the fire door is opened, so that it will not obstruct the door-opening when fuel, such as coal, is introduced therethrough into the fire box, and so that it will not be in a position to hamper the efforts of the fireman in spreading the fuel and arranging the fuel bed; but which, nevertheless, will be placed in the most favorable position over the fire for preheating the air whenever the door is closed.

Another purpose of the invention is to provide a preheater which will retain the air therein until it becomes sufficiently warm before discharging it into the fire box.

The invention also aims to provide a device having but few parts which may be economically manufactured and assembled.

Other objects and advantages will appear in the course of the following description of a preferred embodiment of the invention.

In the accompanying drawings forming part of this specification, in which like numbers of reference denote like parts wherever they occur.

Figure 1 is a fragmentary vertical sectional view through the front wall and fire door of a furnace;

Figure 2 is a plan view of the device as it appears when detached;

Figure 3 is a horizontal sectional view taken on the line 3—3 in Figure 4;

Figure 4 is a front view of the anterior portion of the device which is of substantially rectangular box-like formation and is secured to the inner side of the fire door;

Figure 5 is a rear view of one of the hemispheroidal shells which co-operate together

to form the preheating chamber of the device;

Figure 6 is a view of the inside of the shell;

60

Figure 7 is an elevation of the shell; and Figure 8 is a front view of the same.

The device comprises an anterior portion 1 of substantially rectangular box-like formation and having an open front adapted to fit the inner side of the usual fire door 2, having the usual opening 3 therein for the admission of air into the fire box above the level of the fuel, and closing the opening 4 in the front wall 5 of the furnace. The 70

posterior wall 6 of the box 1 has a major opening 7 therein, and minor openings 8 disposed above and below the opening 7. A

pair of hemi-spheroidal shells 9 co-operate together to form a preheating hollow body 75

having an inlet neck 10 at one end, an outlet neck 11 at the opposite end, and an intermediate bulb 12. A flange 13 is formed on the outer end of the neck 10, and is adapted to fit against the rear side of the wall 6 80

around the opening 7. Bolts 14, passing through openings 8 in wall 6 and openings 15, aligned therewith, in flange 13, secure the shells 9 to the box 1. A tubular portion 16

projects centrally from each shell 9 to meet 85

and form a continuation of the tubular portion 16 of its opposing shell 9. A bolt 17, passing through the central openings 18 in

the shells 9 and through the tube 16, secures the opposing shells together. The tube 16 90

forms a baffle which prevents direct passage of the air through the shells 9, and which deflects the air against the enclosing wall of the shells, thus facilitating the heating of

the air by direct contact with the said wall, 95

which is heated by reason of being disposed over the fire in the fire box of the furnace. When installing the device, aligned openings are made in the door 2 and wall 6, respectively, for the passage of bolts 19, 100

whereby the device is secured to the inner side of the door 2. The said openings are preferably formed at the four corners of the said wall and the said door. The opening 7 is preferably disposed closer toward 105

one side of the wall 6 than the other, and the box 1 is installed so that the opening 7 is closest to the hinge side of the door, so that the entire device will pass through the door opening 4 when the door is swung open completely.

In operation, the air passes, in the direc-

tion indicated by the arrows, through the opening 3, the size of which may be regulated in the usual manner by the conventional slide or shutter (not shown), through box 1 and opening 7 into annular chamber 20, wherein it becomes heated and passes out, through the opening 21 in neck 11, into the fire box, where it mingles with the ascending combustible gases, smoke, and un-
consumed carbon particles, and promotes their combustion much more readily and efficiently than if the cold air passed directly from the opening 3 into the fire box without being thoroughly preheated.
15 The large volume of the bulb 12 and the comparatively small size of the discharge opening 21 insures that the air will pass much more slowly through the bulb 12 than through the opening 21. Furthermore, the
20 lower portion of the bulb is usually hotter than the upper portion because of its proximity to the flame, and the air in the lower portion consequently becomes more highly heated than that in the upper portion and
25 rises to the top; thus promoting the circulation and thorough heating of the air in the bulb before it issues through the opening 21. The opening 7 may be larger than the opening 21 to facilitate the flow of air into the bulb 12, and is preferably round. The opening 21 is preferably elongated horizontally so that the air passes therefrom into the fire chamber in a horizontal layer which spreads over the ascending gases.
30 It will be observed that the device may be easily installed in the conventional type of furnace; that it may be readily detached and taken apart for inspection and other purposes; and that it does not obstruct ac-
35 cess to the interior of the fire box through the door opening 4 when the latter is opened to its full extent. It is, also, worthy of note that the smooth rounded form of the wall of the bulb 12 is one which offers a mini-
40 mum frictional resistance to the flow of air along the same, there being no corners or unevennesses to produce eddy currents and other undesirable effects. The parts of the device may be formed of any material suit-
45 able for the purpose, but cast iron is deemed preferable.
Having thus fully described this invention, I hereby reserve the benefit of all changes in form, arrangement, order, or use
50 of parts, as it is evident that many minor changes may be made therein without de-

parting from the spirit of this invention or the scope of the following claims.

I claim:

1. A device for preheating the air supplied to a fire box and comprising a spheroidal shell having a tubular baffle therethrough, and inlet and outlet openings disposed in the shell on diametrically opposite sides of the said baffle, the said shell being formed of hemi-spheroidal sections meeting in a plane passing through the said openings and transversely through the said tubular baffle, and means within the tubular baffle for detachably securing the sections together. 70

2. In a device for preheating the air supplied to a fire box, the combination of a shell of substantially rectangular box-like formation having an open anterior side adapted to be secured against the inner side 75 of the fire box door, and a posterior wall having an opening therein; and a spheroidal shell comprising a pair of co-operating hemi-spheroidal sections having anterior neck portions secured to the posterior wall 80 around the said opening, and having rearwardly projected discharging neck portions.

3. In a device for preheating the air supplied to furnaces, the combination with a furnace having a combustion chamber and 85 an opening leading thereto, of a bulbous body having inlet and outlet openings communicating with said combustion chamber and its opening and a tubular baffle disposed centrally within said bulbous body directly 90 in line with said inlet and outlet openings and substantially at right angles to the horizontal axes thereof, for intercepting the air currents passing through said openings.

4. In a device for preheating the air supplied to furnaces, the combination with a furnace having a combustion chamber and an opening leading thereto, of a bulbous body comprising superposed similar sections and having inlet and outlet openings communicating with said combustion chamber and its opening, a vertical tubular baffle disposed centrally within said body, means within said baffle for securing said sections in assembled arrangement, and a neck portion encompassing said outlet opening and presenting said opening elongated horizontally to deliver a relatively flat layer of air over the combustion chamber. 100

In testimony whereof I hereunto affix my signature:

NERI J. PETITCLERC.
